DESIGN FOR A COMBINATION KNIFE

Ralph G. Bastien, Minneapolis, Minn.

Application December 30, 1944, Serial No. 117,188

Term of patent 14 years

(Cl. D22—3)

To all whom it may concern:

Be it known that I, Ralph G. Bastien, a citizen of the United States and residing in the city of Minneapolis, county of Hennepin, and State of Minnesota, have invented a new, original, and ornamental Design for a Combination Knife of which the following is a specification, reference being had to the accompanying drawing, forming a part thereof, wherein,

I claim:

The ornamental design for a combination knife, as shown.

RALPH G. BASTIEN.
